UNITED STATES PATENT OFFICE

2,417,234

TOOL SETTING HEIGHT GAUGE

Andreas Frederick Otto Calow, Albany, N. Y.

Application June 8, 1944, Serial No. 539,280

1 Claim. (Cl. 33—185)

1
This invention relates to gauges and refers more particularly to a gauge for setting the height of a cutting tool in a lathe.

It is understood that the height of the tool is critical in producing good work, the tool being set at center height for most work and other tool heights being set with reference to center height. A very small deviation from ideal height seriously impairs efficiency, and practice in setting the tool on center has been to bring the tool closely adjacent to the live or dead center in order to match the height accurately, or to bring the dead center closely adjacent to the tool for the same purpose. Both of these procedures may be inconvenient for reasons too numerous to mention.

An object of the present invention is to provide a means of setting the height of the cutting tool without having to bring the tool to the tip of the live or dead center.

Another object is to provide a means of centering work in a universal chuck or other adjustable work holder.

Another object is to provide a machinist's tool suited to the above purpose and also to many uses of a surface gauge.

Other objects will become apparent from the following specification.

In accomplishing the objects of the present invention it was found desirable to provide an elongated block of metal bearing at one end a vertical standard. On the standard is a rotating sleeve with a longitudinal slot similar to a keyway. Sliding vertically on the sleeve is an arm with a manually operated setscrew projecting into the slot, for locking the arm at any given height. On the tip of the arm is a pointer pivoted at one end to rotate in a plane parallel with the arm. A plurality of magnets are set flush in the under surface of the block.

In operation the block is set on the flat top of the lathe carriage between the toolpost and the center whose height is being used to set the height of the tool. The tip of the pointer is brought adjacent to the tip of the center by rotating the arm or the pointer or both, and is locked at the correct height by the setscrew. The tip of the pointer is then brought adjacent the tip of the tool by rotating the arm or the pointer or both, and the tool may now be conveniently set at the height of the pointer.

The invention will appear more clearly from the following detailed description when taken in connection with the accompanying drawings, showing, by way of example, preferred embodiments of the inventive idea.

2

In the drawings,

Figure 1 is a plan view of the invention being used to set the height of the tool from the dead center.

Figure 2 is a side elevation of the invention.

Figure 3 is an enlarged partial side elevation of the invention, partially in section.

Figure 4 is a horizontal section along the line 4—4 of Figure 2.

Figure 5 is a horizontal section along the line 5—5 of Figure 2.

Figure 1 shows part of a lathe, with work 12 set up in a chuck 11 on the headstock 10. The ways 6 support the carriage 7 and slide 18. The cross feed screw 9 is mostly covered by the slide 18 and chip cover 8 fastened thereto. The tailstock 15, quill 14 and dead center 13 are shown moved in fairly close to the work, yet with sufficient space between it and the headstock 10 to permit a wide variety of chuck work, faceplate work and work between centers. Tool post 19 receives tool holder 20 which receives tool 21. All the above is conventional.

The invention is shown on the flat surface 17 of the carriage 7 between the toolpost and the dead center. The base of the gauge is the block 41 which has holes 37 in its under surface 39 to receive magnets 38 which hold it in place on any magnetic surface even when the arm and pointer 30 are extended perpendicular to the block. The block is of hardened construction and may be clamped in a toolpost when being used in other applications. The end portion 35 of the block has been relieved considerably from the top surface 40 in order to permit a greater downward adjustment of the arm as described hereafter. Cylindrical standard 31, with collar 34, is fixed in vertical position on end portion 35 by countersunk screw 36. Sleeve 32 slips snugly over standard 31 and is micrometrically shorter, so that collar 28 held by screw 27 bears on standard 31 rather than on sleeve 32, and sleeve 32 has substantially no axial movement but rotates freely. Sleeve 32 bears an exterior recess in the form of a longitudinal slot 33. The arm 26 has on one end a downwardly extending sleeve 30 which slips snugly on sleeve 32 and is threaded for a setscrew 29 which engages slot 33. Since collar 34 has the same outside diameter as sleeve 32 sleeve 30 can be slipped down as far as portion 35. A series of holes 42 in arm 26 provide lightness. The outer end of arm 26 is threaded for screw 24 which has a shoulder 25 between the thread and head which shoulder is micrometrically higher than the thickness of pointer 23, so that pointer 23 pivots freely

on shoulder 25 but has no substantial deviation from a plane parallel to the plane of arm 26. The outer half of pointer 23 tapers slightly and terminates in an end surface 22 perpendicular to the axis, with corners 43 and 44.

In operation the gauge is placed on the flat surface 17 of carriage 7 as shown. The arm and pointer both being pivoted, it is very easy to bring end 22 adjacent the dead center, and the height may now be adjusted exactly by slipping arm 26 up or down sleeve 32 and locking it by setscrew 29. This height can now be transferred to the tool by swinging arm 26 or as illustrated swinging pointer 23, or by swinging both.

For precision transfer of height, the arm will be set so that the top or bottom surface of the pointer is in the horizontal plane of the dead center point.

It may be found convenient to use the corner point 44 for setting the height of the arm, and the corner point 43 in setting the height of the tool, or vice versa if the height is being taken from the live center, in which case the block 41 would be on the surface 16 of carriage 7.

The gauge may obviously be used to center a piece of work in a chuck or on a face plate.

By the use of a shim between collar 28 and sleeve 32 or other means of making sleeve 32 rotate less freely, the gauge may be used in many applications as a surface gauge.

It is apparent that the specific illustration shown above has been given by way of illustration and not by way of limitation, and that the structures above described are subject to wide variation and modification without departing from the scope or intent of the invention, all of which variations and modifications are to be included within the scope of the present invention.

What is claimed is:

A gauge, comprising, in combination, an elongated base including a substantially heavy body portion and an end portion located upon one side of said body portion and being of lesser height than said body portion, magnets in said body portion for holding the gauge upon a magnetizable surface, a cylindrical standard vertically mounted on said end portion, said end portion having a counterbore formed therein for receiving the lower end of said standard, said standard having an enlarged collar portion adjacent the lower end thereof and engaging the upper surface of the end portion of said base, a tubular sleeve swingably mounted upon said standard, the diameter of said sleeve being the same as that of the collar portion, whereby said sleeve forms a continuous supporting surface therewith, means preventing substantial axial movement of said sleeve on said standard while permitting rotation of said sleeve on said standard, an arm having a sleeve portion swingably and slidably mounted on said sleeve, means for locking the sleeve portion of said arm at various heights on said sleeve, and a pointer swingably mounted upon the outer end of said arm.

A. F. OTTO CALOW.
